UNITED STATES PATENT OFFICE.

WILLIAM LOUIS DISMUKES, OF NASHVILLE, TENNESSEE, ASSIGNOR OF ONE-
THIRD TO ROBERT J. LYLES, OF SAME PLACE.

COUPLING FOR IRON BEDSTEADS.

SPECIFICATION forming part of Letters Patent No. 632,254, dated September 5, 1899.

Application filed May 4, 1899. Serial No. 715,578. (No model.)

To all whom it may concern:

Be it known that I, WILLIAM LOUIS DISMUKES, a citizen of the United States, residing at Nashville, in the county of Davidson 5 and State of Tennessee, have invented a new and useful Coupling for Iron Bedsteads, of which the following is a specification.

This invention relates to means for connecting the side and end rails of an iron bedstead to the end posts thereof, and has for its object to provide a simple and improved coupling adapted to detachably connect the rails to the posts, so as to facilitate the setting up and taking apart of the bedstead and 15 at the same time to connect the parts firmly together, whereby movement and loosening thereof are effectually prevented.

To these ends the present invention consists in the combination and arrangement of 20 parts, as will be hereinafter more fully described, shown in the accompanying drawings, and particularly pointed out in the appended claims.

In the drawings, Figure 1 is a perspective 25 view showing the invention applied to connect a side and an end rail to the corner-post of a bedstead. Fig. 2 is a longitudinal sectional view thereof, taken in the plane of the side rail of the bedstead. Fig. 3 is a horizontal transverse sectional view. Figs. 4 and 5 30 are detail perspective views of the two members of the coupling. Fig. 6 is a longitudinal sectional view of a modified form of coupling. Figs. 7 and 8 are detail perspective views of 35 the members thereof.

Referring to the accompanying drawings, it will be seen that the coupling comprises a semitubular member 1 and a tubular cap member 2, adapted to embrace the member 1 40 and connect the two members together.

By particular reference to Fig. 4 it will be seen that the semitubular member 1 is provided with a pair of internally-threaded sockets 3, projecting transversely outward from 45 the convex side of the member and intermediate of the ends thereof. These sockets preferably extend at right angles to each other and are braced by means of a web 4, extending between the same. It will be understood 50 that these parts are to be formed integral, so

as to provide a strong and durable coupling-head. The side and end rails 5 and 6, respectively, are adapted to have their ends externally screw-threaded and removably fitted into the respective sockets 3, thereby connecting the rails together at the corners of the bedstead. The member is also provided with a pin or lug 7, extending laterally from the concave side intermediate of the ends thereof and extending in the plane of one of 60 the sockets.

As shown in Fig. 5, the cap member of the coupling comprises a complete sleeve or tube having one side thereof open or cut away longitudinally for a suitable distance and 65 adapted to be slipped upon the semitubular member, so that the opposite longitudinal sides of the opening in the cap member will embrace the opposite longitudinal sides of the semitubular member. By reference to Fig. 70 1 it will be noted that the upper end of the cap member embraces the upper end of the semitubular member, and the transverse shoulder 8, formed by the opening in the cap member, rests upon the upper sides of the 75 sockets 5 and 6, whereby the cap member is prevented from slipping downward out of engagement with the semitubular member. It will be understood that the cap member is necessarily of larger diameter than the other 80 member which it embraces, and therefore the cap member is provided with a filling or the wall of the member opposite the cut-away portion thereof is thickened, as at 9, for the entire length and half of the circumferential 85 width thereof. This thickened portion or filling of the cap member ends abruptly in diametrically opposite shoulders 10, extending the entire longitudinal length of the member and adapted to fit flush against the opposite 90 longitudinal edges of the semitubular member, as clearly indicated in Figs. 2 and 3 of the drawings.

In applying the coupling members to an end post of a bedstead the semitubular member 95 is first fitted thereto, the pin or shoulder 7 being received in a suitable opening 11, formed transversely in the hollow or tubular post 12, as clearly indicated in Figs. 2 and 3 of the drawings. Then the cap member is slipped 100

upon the semitubular member from above and embraces the same, as hereinbefore described. It will now be understood that the purpose of the filling 9 or thickening of the 5 wall of the cap member is to complete the tube or sleeve of which the semitubular member forms a part, and thereby firmly clamp the post between the latter and the filling 9, whereby movement of the parts upon the post 10 is effectually prevented. By reason of the pin fitting in the hole provided in the post the semitubular member carrying the sockets is supported upon the end post, and the cap member embracing the post and the semi- 15 tubular member the latter is held against the post and the pin or shoulder is prevented from becoming disengaged from the opening in the post. Thus it will be seen that the side and end rails of the bedstead may be conveniently connected to the end posts and effectually held thereto and yet permit of the ready removal of the parts when so desired.

In the modified form of the invention the solid end post is provided with an annular 20 enlargement or shoulder 13, and the semitubular member is provided with a transverse shoulder 14 upon the concave side thereof, which is adapted to rest upon the upper side of the annular shoulder 13 provided upon the post. Also the cap member is provided with an inner annular shoulder 15, located opposite the cut-away portion thereof and adapted to rest upon the upper side of the shoulder of the post, whereby the 25 two members are connected to the post. In each of the members of this latter form of the invention the complementary grooves 16 and 17, located above the shoulders 14 and 15, are reduced in size to closely fit the post, so 30 that the lower portions of the grooves may fit the enlargement or shoulder 13, and thereby prevent movement of the members upon the post. This modified form of coupling is intended to provide a connection between the 35 same and a solid post in which it would not be convenient to use the pin connection, as hereinbefore described, for a tubular post.

The present invention provides an exceedingly simple and practical means for connecting the side and end rails to the end posts of a bedstead, being adapted for use in connection with tubular or solid posts and in either case fitting snugly the post, so as to prevent movement and loosening of any of 50 the parts of the device. Furthermore, it will be understood that the coupling may be of angular form instead of rounded, as shown, so as to adapt the device to the different shapes of rails and end posts.

60 Although I have shown and described the coupling as used to connect the rails of a bedstead to the end posts thereof, it will be understood that the coupling may be employed to connect the runner-rails to the posts 65 of an iron fence in a convenient and effect-

ive manner without changing or altering the device in any particular.

Changes in the form, proportion, size, and the minor details of construction within the scope of the appended claims may be resorted to without departing from the spirit or sacrificing any of the advantages of this invention.

What I claim is—

1. A device of the class described, comprising a semitubular member having means adapted to engage a post, whereby the member may be connected thereto, and a tubular cap member adapted to embrace both the post and the semitubular member, whereby the latter is prevented from becoming disengaged from the post, substantially as shown and described. 75

2. A device of the class described, comprising a semitubular member adapted to have an engagement with a post and provided with divergent sockets having a brace-web therebetween, and a tubular cap member adapted to embrace both the post and the semitubular member, whereby the latter is prevented from becoming disengaged from the post, substantially as shown and described. 85

3. A device of the class described, comprising a semitubular member having means adapted to connect the same to a post and provided with sockets, and a tubular cap member having a portion of one side thereof cut away or open longitudinally and adapted to embrace the post and the upper portion of the semitubular member, the transverse shoulder 100 of the cap member formed by the cut-away portion thereof being adapted to rest upon the sockets of the semitubular member, whereby the cap member is held upon the semitubular member, substantially as shown and described. 105

4. A device of the class described, comprising a semitubular member having means adapted to engage a post and provided with sockets, and a tubular cap member adapted 110 to embrace both the post and the semitubular member and provided with a longitudinal enlargement or filling adapted to contract the interior of the cap and coöperate with the semitubular member to fit snugly the post and thereby prevent movement of the device upon the post, substantially as shown and described. 115

5. In a device of the class described, the combination with a post having a lateral opening formed therein, of a semitubular member 120 having a pin or lug adapted to fit within the opening in the post and provided with sockets, and a tubular cap member adapted to embrace both the post and the semitubular member, substantially as shown and described. 125

6. In a device of the class described, the combination with a post having a lateral opening formed therein, of a semitubular member having divergent sockets projecting laterally from the convex face of the member, and a 130

pin or lug projecting laterally from the concave face of the member in the plane of one of the sockets, and a tubular cap member adapted to embrace both the post and the 5 semitubular member, whereby the pin or lug of the latter may be held within the opening formed with the post, substantially as shown and described.

In testimony that I claim the foregoing as my own I have hereto affixed my signature in the presence of two witnesses.

WILLIAM LOUIS DISMUKES.
